CLAIM

The ornamental design for a tequila bottle cover set, as shown and described.

DESCRIPTION

FIG. 1 is a front elevation view of a tequila bottle cover set showing my new design installed on a square bottle, the bottle shown in broken line is for illustrative purposes only and forms no part of the claimed design;

FIG. 2 is a left side elevation thereof, the right side being a mirror image of that shown;

FIG. 3 is a rear elevation view thereof;

FIG. 4 is a top plan view thereof;

FIG. 5 is a top plan view thereof taken along line 5—5 of FIG. 1;

FIG. 6 is a bottom plan view thereof;

FIG. 7 is a front elevation view of an alternate embodiment of a tequila bottle cover set showing my new design installed on a round bottle, the bottle shown in broken line is for illustrative purposes only and forms no part of the claimed design;

FIG. 8 is a left side elevation thereof, the right side being a mirror image of that shown;

FIG. 9 is a rear elevation view thereof;

FIG. 10 is a top plan view thereof;

FIG. 11 is a top plan view thereof taken along line 11—11 of FIG. 7; and,

FIG. 12 is a bottom plan view thereof.

The criss-cross pattern shown on random areas of the scarf portion of the design is repeated uniformly throughout the area shown.
